UNITED STATES PATENT OFFICE.

STEPHEN C. HOWARD, OF PROVIDENCE, RHODE ISLAND, ASSIGNOR TO THE HOWARD STERLING COMPANY, OF SAME PLACE.

DESIGN FOR A DISH.

SPECIFICATION forming part of Design No. 22,313, dated March 28, 1893.

Application filed December 12, 1892. Serial No. 454,972. Term of patent 7 years.

To all whom it may concern:

Be it known that I, STEPHEN C. HOWARD, of Providence, in the county of Providence and State of Rhode Island, have invented and produced a new and original Design for a Dish or Similar Article, of which the following is a specification, reference being had to the accompanying drawings, forming part thereof.

Figure 1 represents a view of a dish illustrating the general effect of my design. Fig. 2 is an enlarged view of a portion of a dish more clearly showing the details of the design indicated in Fig. 1.

The leading features of my design for dishes consist in the alternate plain and pierced panels or sections, the outer borders for the plain sections formed of scrolls slightly foliated and combined in places with shell-like ornaments, the inner continuous shell-like border, and the heavily-scrolled ornaments interspersed with foliations forming the pierced sections.

Numeral 2 in the drawings represents the central portion of a circular dish or plate, or the semicircular end of a long tray; surrounding this central portion is a continuous shell-like

border 3 and beyond this are the alternate panels 4 and 5, the plain panels 4 have outer borders formed by the scrolls 6—6 having the foliations 7 and the shell-like ornaments 8—8. 30 The panels 6 are perforated to correspond to the shape of the ornaments and have the side-scrolls 11—11 which are joined by the foliation 12 with the ornament 13, this being in turn connected by irregular scrolls with the 35 side-scrolls 9 and 10. Below the scrolls 11—11 is the displayed foliation 14 connected with the border 3 by the small scrolls 15—15, and at either side of this foliage is an irregular foliage-scroll 16 and 17. Between the scroll 16 40 and the side scrolls 9 is a foliated scrolled-ornament 18, and the scroll 17 is connected by its foliations with the side-scrolls 10.

What I claim is—

The design for a dish or similar article as 45 herein shown and described.

In witness whereof I have hereunto set my hand.

STEPHEN C. HOWARD.

Witnesses:

HENRY J. MILLER,
M. F. BLIGH.
